JUG

Merritt W. Martin, Jr., Saline, Mich., assignor to Hoover
Ball and Bearing Company, Saline, Mich.

Filed Oct. 22, 1964, Ser. No. 82,283

Term of patent 14 years

(Cl. D58—5)

FIG. 1

FIG. 2

FIG. 3

FIG. 4

FIGURE 1 is a side elevational view of a jug, showing my new design;

FIGURE 2 is a rear elevational view thereof;

FIGURE 3 is a front elevational view thereof; and

FIGURE 4 is a top plan view thereof.

The dominant features of my design reside in the portions shown in full lines.

I claim:

The ornamental design of a jug, as shown and described.
